DESIGN FOR A SKI SLED OR SIMILAR
ARTICLE

Chester Sig Anderson, St. Charles, Ill.

Application September 27, 1946, Serial No. 133,618

Term of patent 14 years

(Cl. D34—15)

To all whom it may concern:

Be it known that I, Chester Sig Anderson, a citizen of the United States, residing at St. Charles, in the county of Kane and State of Illinois, have invented a new, original, and ornamental Design for a Ski Sled or Similar Article, of which the following is a specification, reference being had to the accompanying drawing, forming a part thereof.

In the drawing:

Fig. 1 is a view in side elevation of a ski sled or similar article, embodying my new design;

Fig. 2 is a top plan view thereof; and

Fig. 3 is a view in end elevation thereof.

I claim:

The ornamental design for a ski sled or similar article, substantially as shown.

CHESTER SIG ANDERSON.
